UNITED STATES PATENT OFFICE.

FRANK J. MINER, OF DETROIT, MICHIGAN.

TRACTOR.

1,231,408.

Specification of Letters Patent. Patented June 26, 1917.

Application filed May 13, 1916. Serial No. 97,253.

To all whom it may concern:

Be it known that I, FRANK J. MINER, a citizen of the United States of America, residing at Detroit, in the county of Wayne and State of Michigan, have invented certain new and useful Improvements in Tractors, of which the following is a specification, reference being had therein to the accompanying drawings.

10 This invention relates to a bearing wheel for heavy service vehicles, such as automobile trucks, tractors or the like, of the type wherein a continuous linked periphery of suitable segments is brought into use in such 15 manner as always to impose a comparatively large bearing area upon the surface of the ground traversed. The device involves a construction which transfers the weight directly to the member of the periphery that is on the ground without in any way binding the other parts, and likewise includes driving means which tend to advance the member without causing it to slip when in contact with the ground.

20 25 The invention consists in the matters hereinafter set forth, and more particularly pointed out in the appended claims.

Referring to the drawings,

Figure 1 is a view in side elevation, partly 30 broken away and in section and with plate removed, of a structure that embodies features of the invention;

Fig. 2 is a plan view thereof assembled;

Fig. 3 is a view taken in section on line 35 III—III of Fig. 1;

Fig. 4 is a view in detail of a tread segment;

Fig. 5 is a view in elevation showing the application of a tractor to a truck;

40 Fig. 6 is a view partly broken away and in section, of a modification of the tractor;

Fig. 7 is a view in section taken on or about line VII—VII of Fig. 6;

Figs. 8 and 9 are views in detail of a segment of the modified form; and

Figs. 10, 11 and 12 are views in detail of slight modifications of the spacing wheels.

In the drawings a track plate 4, is provided to which a side plate 2 may be secured by suitable means, as for example bolts or holding members 3. The track plate is transversely gained or cut away between its ends to provide clearance for a main driving gear 5 that may be mounted 55 on a shaft 6 journaled in the bearing.

A series of segments 7 are arranged alter-

nately with other corresponding segments 8 to which they are connected by pivot members 9. A set of spacing wheels 10 are mounted on pivot members 9 in the plane 60 of the spacing member 4, the parts being so proportioned that the wheels 10 roll continuously on the marginal surface afforded by the member 4. Preferably, as indicated in Fig. IV, the wheels 10 are carried in 65 suitable recesses formed in the members 7 and 8. Dust guards 11 are formed on the faces of the members 7 and 8 in such relation to the overlapping end portions of the adjacent pair of members, as to substantially close the wedge shaped gap between them, and as indicated in Fig. 1, to act to 70 expel any dirt that would otherwise tend to be drawn between the members 7 and 8 as they assume different angular relation in 75 coming into contact with the ground.

The parts are further housed by a cover plate 12 which is secured to the spacing plate 4 by suitable screws or the like and may have an outboard bearing 13 for the 80 journal 6.

Where the device is to be used as a tractor with the wheel 5 in the position indicated, rack links 14 are pivoted together by the members 9 so as to form a continuous rack 85 in engagement with the wheel 5.

It is to be understood that the bearing 1 (here shown diagrammatically) and the mating support 13 with intermediate parts are so disposed and arranged that they may 90 be mounted on the standard driving axle of a truck or the like. When so mounted with the driving gear in place, the weight from the truck is transmitted in a direct line through the large bearing wheels and cam plate or track plate to the links or segments as they strike the ground so that there is practically no weight to be carried by the pivot members of the device. Furthermore the action of the gear wheel on the rack is 95 such that the device rolls on the lower rack and corresponding portion of the track plate while it is driving forward the upper or slack portion.

In the modification shown in Fig. 6, the 105 segments 14 are linked together in overlapping relation and each are provided with recesses 15 in which rollers or spacing wheels 16 are journaled on the pivot pins 17 that secure the links in relation. Because of the 110 overlapping of the links or segments and the housing in the recesses 15 of the rollers

16 it is necessary to broaden the track plate and this is accordingly done as indicated at 18, and furthermore the periphery of the track wheel is grooved so that so far as active operation is concerned, an outer plate 5 19 which is herein shown corresponding to the cover plate 12 shown in Fig. 3, may be omitted as there is no side thrust in the members.

10 Because also of this construction, the gearing may be omitted and while in Fig. 7 there is shown a gear 20 meshing into racks 21 carried by the pivots, still this can be readily taken off in case the assembled device is used merely as a bearing wheel and 15 not for tractor purposes.

In order to prevent this side play that has been above alluded to in reference to plates 19 and 20 or the corresponding plates 12 20 and 2 of the other type, the spacing wheels may be given the dress on the periphery shown in Figs. 10, 11, and 12, that is, they may have any grooved or flanged periphery which assists, when coöperating with a correspondingly formed rim on the track plate, 25 in maintaining the links or sections in lateral alinement without imposing any end thrust whatever through the pivot pins to the plates which merely act as dust protectors.

30 As a result of this construction a wheel is obtained which provides a very broad bearing surface that does not tend to slip, that practically clears itself of dirt, and that 35 permits the free operation of the parts as they are well housed from dust or mud. With the racks omitted and either with plain links replacing them or with no such parts, the device becomes a bearing 40 wheel that carries enormous loads over soft ground without difficulty.

45 As a further result of the arrangement of the device the hub which is herein shown largely diagrammatically is so disposed and the portion of the parts is such that the tractor wheel may be readily mounted on any standard driving axle or hub in place of a conventional traction bearing wheel. That is, the proportions of the wheel are so 50 arranged that the vertical diameter is substantially that of a tractor wheel and accordingly it may be substituted for such wheel on any vehicle. This is the arrangement shown in Fig. 5.

55 A further result of the construction is the generous proportions of the spacing wheels which while completely housed in the recesses of the segments, are still of such diameter that the rolling contact with the 60 track plate practically eliminates all load friction. The large size of the spacing wheels also eliminates any noise, to a large extent, that is common in devices of this character wherein small rollers are used to 65 carry a linked tread.

Obviously changes in the details of construction may be made without departing from the spirit of my invention and I do not care to limit myself to any particular form or arrangement of parts.

70

What I claim is:—

1. A bearing wheel for vehicles comprising a side plate, a track plate secured thereto, a cover plate secured on the track plate, oppositely disposed segments having recessed end portions pivoted together in overlapping relation to form an endless link tread member encircling the track plate between the side and cover plates, spacing wheels mounted between the overlapping portions of the segments at the pivotal points thereof in rolling contact with the margin of the track plate, and a dust guard on each segment filling the interval between the overlapping contiguous pairs of segments.

75

2. A bearing wheel for vehicles comprising a side plate, a track plate secured thereto, oppositely disposed segments having recessed end portions pivoted together in overlapping relation to form an endless link tread member encircling the track plate between the side and cover plate, spacing wheels mounted between the overlapping portions of the segments at the pivotal points thereof in rolling contact with the margin of the track plate, and a dust guard on each segment filling the interval between the overlapping contiguous pairs of segments.

80

3. A bearing wheel for vehicles comprising a side plate, a track plate secured thereto, oppositely disposed segments having recessed end portions, pivoted together in overlapping relation to form an endless linked tread member encircling said track plate, spacing wheels having flanged peripheries engaging the correspondingly faced peripheries of the track plate mounted in the recesses of the segments at the pivotal points thereof in rolling contact with the track plate, and a dust guard on each segment filling the interval between the overlapping contiguous pairs of segments.

85

4. A bearing wheel for vehicles comprising a side plate, a track plate secured thereto, oppositely disposed segments having recessed portions, and pivoted together in overlapping relation to form an endless link tread member encircling said track plate, spacing wheels housed in the recessed portions of the segments and journaled at the pivotal points thereof in rolling contact with the track plate, the wheel and track contacting portions being correspondingly faced to prevent lateral displacement, and a dust guard on each segment filling the interval between the overlapping contiguous pairs of segments.

90

5. A bearing wheel for vehicles, comprising

100

105

ing a side plate, a track plate secured thereto, oppositely disposed segments having recessed end portions, pivoted together in overlapping relation to form an endless link tread member encircling said track plate, spacing wheels in the recesses of the segments at the pivotal points thereof in rolling contact with the track plate, rack links articulating on the pivotal connections of the segments, and a driving gear in mesh with the rack links rotatably mounted in the plates in substantially concentric relation with the link tread member.

6. A bearing wheel for vehicles, comprising a side plate, a track plate secured thereto provided with a peripherally grooved and flanged margin, oppositely disposed segments pivoted together in overlapping relation to form an endless link tread member encircling the track plate, spacing wheels journaled on the pivot connections of the segments and housed by the segments having flanged peripheries engaging the periphery of the track plate, a dust guard on each segment filling the interval between the overlapping contiguous pairs of segments, rack links connecting the pivot members of the segments, and a gear mounted on the track plate concentrically with the periphery thereof in mesh with the rack links.

7. A bearing wheel for vehicles comprising a side plate, a track plate secured thereto, oppositely disposed segments having recessed end portions pivoted together in overlapping relation to form an endless link tread member, encircling the track plate, spacing wheels mounted between the overlapping portions of the segments at the several pivotal points thereof in rolling contact with the margin of the track plate, the spacing wheels being of a diameter closely approaching the width of the segments, and a dust guard on each segment filling the interval between the overlapping contiguous pairs of segments.

8. A bearing wheel for vehicles comprising a side plate, a track plate secured thereto, oppositely disposed segments having recessed end portions, pivot members secur-

ing the segments together to form an endless link tread member encircling the track plate, spacing wheels mounted in the recessed portions of the segments on the pivot members of sufficient diameter to project beyond the margins of the segments, and arranged in rolling contact with the margin of the track plate, and a dust guard on each segment filling the interval between the overlapping contiguous pairs of segments.

9. A bearing wheel for vehicles comprising a side plate, a track plate secured thereto, a set of oppositely disposed segments having recessed end portions, pivots securing the overlapping end portions of the segments to form an endless link tread member encircling the track plate, spacing wheels mounted on the pivot members in the recesses of the segments, in rolling contact with the margin of the track plate and a dust guard on each segment filling the interval between the overlapping contiguous pairs of segments, the contacting margins of the track plate and wheel being arranged to prevent lateral displacement of the parts relative to each other.

10. In a motor vehicle, the combination of a standard bearing and driving axle, of a traction bearing wheel comprising a track plate adapted to be journaled on the axle, a driving gear journaled adjacent the plate adapted to be secured to the drive shaft of the axle, a series of segments having inner recessed marginal portions, pivots connecting the segments, spacing wheels on the pivots engaging the marginal face of the track plate and maintaining the segments therearound as a linked tread, rack links connecting the pivots in mesh with the driving gear, and dust guards on each segment between the adjacent end portions of the companion segments.

In testimony whereof I affix my signature in the presence of two witnesses.
